LADY'S SANDAL OR SIMILAR ARTICLE

Robert T. Wiseman, Canton, Ohio

Application March 22, 1951, Serial No. 14,593

Term of patent 14 years

(Cl. D7—7)

To all whom it may concern:

Be it known that I, Robert T. Wiseman, a citizen of the United States, residing at Canton, in the county of Stark and State of Ohio, have invented a new, original, and ornamental Design for a Lady's Sandal or Similar Article, of which the following is a specification, reference being had to the accompanying drawing, forming part thereof, in which:

Figure 1 is a plan view of a shoe or similar article showing my new design; and

I claim:

The ornamental design for a lady's sandal or similar article, substantially as shown.

ROBERT T. WISEMAN.
